S. Z. DE FERRANTI.

UNDER WATER VEHICLE.

APPLICATION FILED MAY 20, 1909.

981,546.

Patented Jan. 10, 1911.

UNITED STATES PATENT OFFICE.

SEBASTIAN ZIANI DE FERRANTI, OF GRINDLEFORD BRIDGE, ENGLAND.

UNDER-WATER VEHICLE.

981,546.

Specification of Letters Patent. Patented Jan. 10, 1911.

Application filed May 20, 1909. Serial No. 497,297.

To all whom it may concern:

Be it known that I, SEBASTIAN ZIANI DE FERRANTI, a subject of the King of Great Britain and Ireland, and residing at Grindleford Bridge, in the county of Derby, England, have invented certain new and useful Improvements in and Relating to Under-Water Vehicles, of which the following is a specification.

10 The present invention relates to water vehicles such as submarines and torpedoes, which in certain cases have to operate below the surface of the water. Vehicles of the type in question which are adapted to work 15 below the water are hereinafter referred to generically as submersibles. In the case of submarines it is a very common expedient to use two different sets of power plants, one for operating on the surface and one for 20 operating when submersed.

One of the main objects of the present invention is to greatly simplify such installations and in particular to provide improved methods of and means for operating 25 with combustion motors. The common practice with such motors is to oxidize a certain amount of fuel and so generate a comparatively small volume of high temperature 30 gases which must be diluted with some appropriate fluid in order to obtain a workable volume of gas at a workable temperature. Now, in the case of submarines, the additional volume of material which it is necessary to add to the products of combustion 35 may very conveniently be atmospheric air when running on the surface. When submersed, however, atmospheric air is no longer available, and it then becomes necessary to utilize some other fluid. The method 40 of operation I prefer to adopt is to utilize part of the exhaust gases of the combustion motor as added material.

The present invention thus consists in the improved methods of and means for working 45 underwater vehicles of the type indicated hereinafter described, and particularly pointed out in the claims.

My invention may be briefly summarized and exemplified as follows:

50 When above water, the driving may be effected by means of a simple air turbine in which case sufficient air is compressed, not only to burn the combustible, but also to act as the inert matter to utilize properly 55 the heat generated, or the portion of the fluid to be compressed sufficient for complete

combustion may be drawn from the outside air, and the balance of the working fluid from the exhaust after passing through a final cooler and after compression to the 60 maximum pressure. For below water working the only change necessary is to replace the fresh air of the working fluid by air drawn from pressure storage tanks, or from a store of liquid air carried, or by oxygen 65 sufficient to burn the fuel, this oxygen being obtained either from cylinders of compressed gas or from a storage of more or less pure liquid oxygen carried in the vessel. The advantage of this method of working 70 is that no supplementary or additional combustion chamber and nozzle arrangements are required for underwater working, the valve which cuts off the fresh air supply to the compressor being connected to 75 open out the supply from the storage system. Supplementary compressing cylinders may be fitted to the ordinary working pumps or compressors in order to raise the air to the storage pressure, while working on the 80 surface ready for operation submersed.

The accompanying drawing shows a dia- 85 grammatic section through part of a submarine vessel by way of example of my invention.

According to the form of apparatus herein shown as suitable for carrying my invention into effect, the driving motors consist of turbines, a', a^2 , arranged on coaxial shafts, b', b^2 , to rotate in opposite directions, and 90 so drive respectively the propellers c', c^2 . The turbines are supplied with working fluid from the combustion chambers, d, d , by way of expansion nozzles, e, e , the exhaust from the turbines passing through 95 suitable connections, f, f , to a regenerator or cooler, h , and so overboard by way of the pipe, i . The regenerator, h , may take any convenient form, and as shown comprises a series of tubes, k , connected to collecting 100 headers, these tubes being arranged within a suitable casing. The exhaust gases thus pass through the tubes, k , while the fluid to be warmed passes outside them.

As regards operation on the surface, the 105 fuel which may be oil for example, is contained in a tank, m , from which a pump, n , draws by way of the pipe, o , the pump delivering the oil into the combustion chambers by way of the pipes, r . The air for 110 combustion is drawn from the atmosphere by way of the pipe, s , by the pump, t , and

delivered through the pipes, *u*, *v*, into the regenerator, and thence by way of the connections, *u*, and *y*, into the combustion chambers. According to this method of working, 5 sufficient air is taken from the atmosphere not only to completely burn the combustible but also an amount in addition to form a working volume with the products of combustion. The pump, *t*, as shown, may be 10 utilized to deliver into the air storage tank, *x*, by way of the pipe, *z*, when for instance the vessel is in harbor or a supplementary pump, 2, may be fitted, drawing from the atmosphere by way of the pipes, 3 and, *s*, and 15 delivering the compressed air through the pipe 4, into the reservoir, *x*.

When working below the surface atmospheric air in unlimited quantities is no longer available, so that the air necessary 20 for combustion passes under pressure from the reservoir, *x*, through the pipes, *z*, and *v*, to the regenerator, and thus by pipes, *w* and *y*, into the combustion chambers. The additional material to form a workable volume 25 of fluid with the products of combustion, is in this case taken by a pump, 5, which may be driven by gearing, 6, from the propeller shaft, *b'*, from the exhaust port, *i*, by way of the pipe, 7, the exhaust gases having 30 been cooled in the regenerator, and the amount so abstracted is forced through the pipes, 8 and 9, into the combustion chambers.

It is evident that without change in the apparatus the exhaust gases may be used if 35 desired, both when working on the surface and when submersed. In the case of a torpedo for example, which always runs submersed, atmospheric air is in no case available as added material. Suitable valves, 40 two of which are indicated at, 10 and 11, are fitted as required to enable the apparatus described to perform its various functions.

Having now described my invention what I claim as new and desire to secure by Letters Patent is:—

1. In combination in a submersible a combustion motor carried by the same, a combustion chamber therefor, means for introducing into said chamber combustible and 50 an excess of oxidizer, together with means for replacing said excess of oxidizer by a fluid other than said oxidizer under certain working conditions.

2. In combination in a submersible a combustion motor carried by the same, a combustion chamber therefor, means for introducing into said chamber combustible and an excess of an oxidizer, together with means for replacing said excess of oxidizer by inert 60 fluid under certain working conditions.

3. In combination in a submersible a combustion motor carried by the same, a combustion chamber therefor, means for introducing into said chamber combustible and 65 an excess of an oxidizer, together with

means for replacing said excess of oxidizer by exhaust products from said motor under certain working conditions.

4. In combination in a submersible vehicle, a combustion motor carried by the same 70 and means for adding at will to the products of combustion of the fuel for said motor either a certain volume of air or a certain volume of fluid other than air for the purpose set forth.

5. In combination in a submersible vehicle, a combustion turbine carried by the same and means for adding at will to the products of combustion of the fuel for said turbine either a certain volume of air or a 80 certain volume of fluid other than air for the purpose set forth.

6. In combination in an automotor submersible, a combustion motor driving the same and means for adding to the products 85 of combustion of the fuel a certain volume of atmospheric air when running on the surface and a certain volume of fluid other than atmospheric air when submersed.

7. In combination in an automotor submersible, a combustion motor driving the same and means for adding to the products of combustion of the fuel a certain volume of atmospheric air when running on the surface and a certain volume of the motor 95 exhaust gases when submersed.

8. In combination in an automotor submersible, a combustion motor driving the same, and means for adding to the products of combustion of the fuel a certain volume 100 of air or a certain volume of the motor exhaust gases at will.

9. In combination in an automotor submersible, a combustion motor; a combustion chamber therefor; a reservoir for compressed fluid; a pump with a suction connection through the shell of said automotor to the atmosphere and a delivery controllable at will either to said reservoir or to said combustion chamber.

10. In combination in an automotor submersible, a combustion motor; a combustion chamber therefor; a reservoir for compressed fluid; a plurality of pumps; means for connecting the suction of said pump 115 through the shell of said automotor to the atmosphere and means for connecting the deliveries of said pumps to said reservoir together with a connection from one of said delivery connecting means to said combustion chamber.

11. In combination in an underwater automotor, a combustion motor; a combustion chamber therefor; means for cooling the exhaust gases from said motor and a connection 125 from said cooling means to said combustion chamber to pass cooled exhaust gases thereto.

12. In combination in an underwater automotor, a combustion turbine; a combustion chamber therefor; means for cooling the ex- 130

haust gases from said turbine and a connection from said cooling means to said combustion chamber to pass cooled exhaust gases thereto.

5 13. In combination in an underwater automotor, a combustion motor; a combustion chamber therefor; means for cooling the exhaust gases from said motor and a pump with a suction from said cooling means and 10 a delivery to said combustion chamber to pass cooled exhaust gases thereto.

14. In combination in an automotor submersible, a combustion motor; a combustion chamber therefor; a reservoir for compressed fluid; a pump with a suction connection through the shell of said automotor together with a single instrumentality for directing

the discharge of said pump at will either to said reservoir or to said combustion chamber.

20

15. In combination in an automotor submersible, a combustion motor; a combustion chamber therefor; a reservoir for compressed fluid; a pump with a suction connection through the shell of said automotor to the 25 atmosphere together with connections from said pump and said reservoir to said chamber, said connections having a common part.

In testimony whereof, I affix my signature in presence of two witnesses.

SEBASTIAN ZIANI DE FERRANTI.
